UNITED STATES PATENT OFFICE.

FRIEDRICH HEINRICH FLOTTMANN, OF BOCHUM, GERMANY.

VACUUM-PAN.

SPECIFICATION forming part of Letters Patent No. 447,673, dated March 3, 1891.

Application filed October 28, 1890. Serial No. 369,566. (No model.) Patented in Belgium August 13, 1890, No. 91,629.

To all whom it may concern:

Be it known that I, FRIEDRICH HEINRICH FLOTTMANN, a subject of the King of Prussia, residing at Bochum, Prussia, Germany, have 5 invented new and useful Improvements in Vacuum-Pans, (for which Letters Patent have been obtained in Belgium August 13, 1890, No. 91,629,) whereof the following is a specification.

10 My invention relates to vacuum-pans such as are employed in various manufactures for boiling, evaporating, drying, and other purposes; and the object of the improvements is to facilitate the manipulations which have to be carried out with the apparatus and to render it adapted for different purposes besides those mentioned.

In the annexed drawings an apparatus carried out according to my invention is shown 20 by Figures 1 and 2 in sectional elevation in two different positions, Fig. 1 representing the position in which the apparatus is charged and emptied and Fig. 2 the working position. Fig. 3 is a central transverse section corresponding to Fig. 2.

The apparatus is composed of two vessels A and B, inserted one within the other. The outer vessel A has two trunnions 1 2, with which it is mounted in the respective bearings 3 4, and it is provided with the stuffing-boxes 11 12, arranged at a right angle to the axis of the trunnions 1 2. These stuffing-boxes serve as bearings for the trunnions 5 6, with which the inner vessel B is furnished. 35 The trunnion 2 of the vessel A is hollow, and to the same is connected by means of a stuffing-box a pipe 9, serving for the supply of steam, hot or cold water or air, or compressed air, or through which air is exhausted from 40 between the vessels A and B. The trunnion 1 is shown as being hollow also, in view of allowing the same to be utilized for any attachments; but as represented it is closed by a cover. The trunnions 5 6 of the vessel B 45 are both hollow. The trunnion 5 is provided with a screw-plug 18 for allowing it to be opened and closed, while the trunnion 6 is closed by a cap D, formed in one piece with the cover of the stuffing-box 12, and being in 50 consequence stationary relatively to the vessel A, whereas the trunnion 6 rotates therein. The said cap is provided with a tubular

branch piece 13, to which is attached a cock H with flexible pipe 14, leading to an air-pump or other exhauster (not shown in the drawings) and a vacuum-gage G. Moreover, the cap is fitted with a cock E and a tube F, closed at the bottom and adapted to contain a thermometer.

C is a perforated partition-plate or false bottom, and 15 16 are doors.

For turning the outer vessel A, together with the inner one B, from the charging and discharging position, Fig. 1, into the working position, Fig. 2, or vice versa, the trunnion 1 65 is provided with the worm-wheel 7, gearing with the worm 8, which is arranged to be rotated by a crank 17. This turning of the apparatus by a quarter of a revolution can be brought about without disturbance of its connection with the exhauster on account of the flexibility of the pipe 14. The rotation of the inner vessel B within the outer one is produced by a spur-wheel Z, keyed on the end of the trunnion 5, the said spur-wheel being connected when the apparatus is in working position with any suitable driving-gear. (Not shown in the drawings.)

If the apparatus is to be used, it is brought into the vertical or charging position, Fig. 1. 80 The cocks E and H are closed, the screw-plug 18 is removed, a funnel 19 is put in its place, and the substance to be treated is introduced through the same into the vessel B, the substance, if solid, dropping on the perforated 85 plate C. The funnel is then withdrawn again, the plug 18 is reinserted, the apparatus is turned into its horizontal or working position, Fig. 2, cock H is opened and communication thereby established between the exhauster 90 and the vessel B, the heating, cooling, or other medium is introduced through pipe 9 into the space between the vessels A and B, and the vessel B is put in rotation by means of the spur-wheel Z and its driving mechanism. 95 When the operation is finished, the apparatus is brought back to the vertical position, cock H having previously been closed. Any liquid contained in the vessel B may then be drawn off by the cock E. Solid materials are discharged either through the trunnion 5 or through the apertures closed during the operation by the doors 15 16. Whenever these doors have to be removed, the pipe 9 is first

- closed by means of valve 10 and the cock 1 is opened, while the apparatus is in horizontal position for allowing the medium contained in vessel A or water of condensation to issue; but with exception of this case the vessel B may be charged and discharged, and samples may be taken therefrom without education of the heating or cooling medium from the vessel A.
- 10 The apparatus may be employed in breweries and distilleries for boiling and cooling mash and wort, in sugar manufactories for extracting the juice from beet-root slices, in the concentration of solutions of various kinds, 15 in the desiccation of meat, malt, refuse matter for manure, and other materials. Besides it is serviceable for the disintegration of bones while being subjected to heat, and, provided the walls of the vessel B are perforated and 20 the cover of the hollow trunnion 1 is removed, it may also be used as malting apparatus.

I claim as my invention—

1. The combination of the outer vessel A, 25 having the hollow trunnion 1 and the trunnion 2, and stuffing-boxes 11 12, arranged at a right angle to the said trunnions, bear-

ings 3 4 for receiving the trunnions 1 2, an inner vessel B, having hollow trunnions 5 6, with which it is mounted in the stuffing-boxes 30 11 12, pipes in connection with the trunnions 2 and 6, and means for rotating the vessel A in its bearings 3 4 and the vessel B in the stuffing-boxes 11 12, substantially as described.

2. The combination of the outer vessel A, 35 having the hollow trunnion 1 and the trunnion 2, and stuffing-boxes 11 12, arranged at a right angle to the said trunnions, bearings 3 4 for receiving the trunnions 1 2, an inner vessel B, having hollow trunnions 5 6, with 40 which it is mounted in the stuffing-boxes 11 12, pipe 9 in connection with the hollow trunnion 2, the closed stuffing-box cap D on trunnion 6, pipe 13, attached to the said cap, and means for rotating the vessel A in its bearings 3 4 and the vessel B in the stuffing-boxes 45 11 12, substantially as described.

In testimony whereof I have hereunto set my hand in the presence of two subscribing witnesses.

FRIEDRICH HEINRICH FLOTTMANN.
